BENDING MACHINE

Julius B. Milan, Galveston, Tex.

Application May 11, 1943, Serial No. 486,590

2 Claims. (Cl. 153—56)

This invention relates to a bending machine and has particular relation to a machine for bending pipe, structural steel beams and angles and the like.

An object of the invention is to provide a machine of the character described specially designed for bending pipe, rods, structural steel beams and angles and which may be readily adjusted to bend the work to any desired degree of curvature.

It is another object to provide a machine of the character described which is so constructed as to preserve the original, cross sectional contour of the work while it is being bent.

A further object is to provide a machine of the character described wherein the work is readily accessible during the bending operation so that measurements of the work can be easily taken while the bending operation is being carried on.

With the above and other objects in view the invention has particular relation to certain novel features of construction, operation and arrangement of parts, an example of which is given in this specification and illustrated by the accompanying drawing wherein:

Figure 1 shows a plan view of the machine and Figure 2 shows a cross-sectional view thereof taken on the line 2—2 of Figure 1.

Referring now more particularly to the drawing wherein like numerals of reference designate the same parts in each of the figures, a main frame is provided having the side plates or members 16, 16 whose ends are secured to the respective end plates 2, 2.

Secured on the inside of the side plates 16, 16 are the opposed longitudinal tracks 3, 3 on which the respective cross heads are mounted to slide, each cross head comprising the upper and lower plates 7, 7 which are connected to the respective outer plates 5. These cross heads form also gear housings as is illustrated in Figure 2. The cross heads may be adjusted toward and from each other by means of the adjusting screws 4, 4 which are threaded through the respective end plates 2, 2 and whose inner ends have swivelling connections with said cross heads as indicated in Figure 1, and are maintained against detachment by collars 13, 13 pinned thereon.

The screw shafts 4 may be turned to adjust said cross heads. It will be noted that the end plates 5 of the crosshead are notched to snugly receive the corresponding tracks 3 as is shown in Figure 1.

Mounted to rotate in the upper and lower

bearings 18, 18 of said cross heads are the vertical shafts 19, 19 on which the rollers 6a are splined. These shafts are mounted to turn on the anti-friction bearings 17, 17 as shown in Figure 2. Fixed on the shafts 19, within the cross heads, are the screw gears 10 which are driven by corresponding screw gears 11 splined on the shaft 8. This shaft is mounted to rotate in the bearings 9 in the end plates 2 and is retained in place by the collar 12 pinned on one end thereof. The shaft 8 is, preferably, power driven from the other end.

Splined on the upper ends of the shafts 19 are the rollers 6a, 6a which are retained thereon by the cap screws 14.

There is a lateral frame which extends across the main frame midway between the main frame cross heads as shown in Figure 1 and which is firmly secured to said main frame. This lateral frame is composed of the said members 16a, 16a, connected at their outer and inner ends by the end plates 2a, 2a. Secured on the inner sides of side members 16a, 16a are the longitudinal tracks 3a, 3a. Mounted to move on these tracks is the cross head comprising the upper and lower plates 7a, 7a and the end plate 5a whose ends are notched to receive the tracks 3a. An outwardly threaded shaft 4a is threaded through the outer end plate 2a and has a swivelling connection with the plate 5a of the cross head and is held against detachment therefrom by a collar 13a pinned onto the inner end of the said screw shaft 4a. This shaft may be turned by a crank and the corresponding cross head thus adjusted. Securely anchored to the cross head 7a, 7a and upstanding therefrom there is a spindle similar to spindle 19 and on which there is mounted to rotate the die roller 15a. This roller is retained on the spindle by the cap screw 14.

The work to be bent may be placed in the rollers 6a, 6a and the die roller 15a then adjusted by the shaft 4a against said work. The rollers 6a, 6a may be adjusted the required distance apart so as to give the desired degree of curvature to the work to be bent. Power may then be applied, through the shaft 4a, to the die roller 15a so as to bend the work and the shaft 8 may be slowly rotated to rotate the rollers 6a to move the work along as it is bent. The teeth or threads of the gears 10, 11 are so pitched that the rollers 6a will turn in the same direction. It is obvious that the work will be accessible for the application of a template thereto for measuring the curvature of the work. The work may be moved back and forth and the required

pressure applied and the required adjustments made until the desired shape has been attained.

The rollers 6a may have annular grooves 6b to receive the flange of an angle iron and the roller 15a may be substantially cylindrical to fit against the plane side of said angle iron; however, these rollers may be made of any shape to conform to the shape of the work being bent.

The idler rollers 24, 24 are provided which are mounted on the movable arms 25, 25 whose inner ends are pivoted on the respective shafts 19, 19. The idler rollers 24 are mounted to rotate on the spindles 28 which in turn, have their lower ends fixed to the bases 30, 30 and these bases are secured to the respective arms 25 by the set screws 31.

They are adjustable toward and from the rollers 6a depending on the thickness of the angle being bent. The rollers 24 have the bushings 29 therein around the spindles 28.

The rollers 6a, 15a and 24 are maintained against detachment from their respective shafts or spindles by cap screws 14.

Adjacent the framework there is a table 34 for the convenience of the workman carrying on the work. This table has a transverse slot 27. The outer ends of the arms 25 have the longitudinal slots 35, 35. Extended through the respective slots 35 and through the slot 27 are the rods 32 whose upper ends are threaded and pinned on the lower ends of these rods are the clamp collars 33.

Threaded onto the upper ends of the rods 32 are the outwardly knurled thumb screws 26 by means of which the arms 25 may be maintained at any point of adjustment.

These arms will be adjusted so that the pressure rollers 24 will be in a radial position relative to the arc of curvature of the work and they will prevent a change in the cross sectional contour of the angle iron or other structural member being bent, that is, they will maintain the flanges in their original right angular relation and prevent the distortion as a result of the bending operation.

The drawing and description are illustrative merely while the broad principle of the invention will be defined by the appended claims.

What I claim is:

5. A machine for bending elongated objects formed of bendable material, comprising a framework, a pair of oppositely arranged cross heads thereon, means for adjusting said cross heads toward and from each other, a shaft mounted on each cross head, a work receiving roller fastened on each shaft with its axis perpendicular to the plane of movement of the cross head, power means for rotating said shafts and rollers, a cross head on the framework movable in a direction perpendicular to the work on said rollers, an idler die roller on the last mentioned cross head, means for actuating said die roller to apply pressure to the work receiving rollers, idler pressure rollers on the framework arranged to bear against the work opposite the work receiving rollers, and means to adjust the idler pressure rollers to maintain them in radial position relative to the arc of curvature of the work.

25. A bending machine comprising a main frame having side members and end members secured together, inside longitudinal tracks on the side members, cross heads mounted to slide on said tracks and spaced apart, adjusting screws threaded through said end members and having swivelling 30 connections with the cross heads, rollers on the cross heads, gearing housed within the cross heads and operatively connected with the rollers to rotate the same, a shaft for driving the gearing, a lateral frame which extends across the main frame between the cross heads and which is secured to the main frame, said lateral frame comprising side members and outer and inner end members, inside longitudinal tracks on the side members of the lateral frame, a cross head mounted to move on said tracks, an idler roller mounted on said last mentioned cross head, a shaft threaded through the outer end member of the lateral frame and having a swivelling connection with the corresponding cross head.

45. JULIUS B. MILAN.
